UNITED STATES PATENT OFFICE.

GEORGE H. ADAM, OF CINCINNATI, OHIO.

SAFETY SAW-GUARD.

1,101,515.

Specification of Letters Patent. Patented June 30, 1914.

Application filed June 27, 1913. Serial No. 776,195.

To all whom it may concern:

Be it known that I, GEORGE H. ADAM, a citizen of the United States, resident of Cincinnati, in the county of Hamilton and State of Ohio, have made a certain new and useful Invention in Saw-Guards; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a side view of the invention as applied. Fig. 2 is an end view of the same. Fig. 3 is a plan view of the invention.

The invention has relation to saw guards, having for its object to provide a guard which will be equally useful when the table is level, and when it is tilted to a high angle.

Other objects and advantages will hereinafter appear.

The invention consists in the novel construction and combinations of parts, as hereinafter set forth.

In the accompanying drawings, illustrating the invention, the numeral 1 designates the saw, 2 the saw table, and 3 the supporting frame, the saw being arranged at one side of the table, so that the table may be tilted to the desired angle in the usual manner. Overlying the saw is the top guard 4, preferably pivoted at its rear end at 5 to the standard 6, located in the rear of the saw, the yoke 6' of said standard being bolted to the frame 3 in the usual manner. The top guard is preferably provided at its rear end with a vertical slot 7, in which fits the plate-form upper end portion 8 of said standard, to prevent any lateral movement of the guard, the pivot pin passing through the branches of the rear end of the guard at the sides of the slot and through the standard. The forward end of the top guard is bent downwardly at 9 toward the saw table, and is provided with an upturned or cam end 10, a roller 11 being carried by the forward end of the guard and resting normally upon the saw table, reducing friction when the wood is passed to the saw between the roller and the table, the top guard being lifted upon its pivot in this operation. At each side of the top guard is provided a lateral shield or guard 12, pivoted at its front end to the front end of the top guard

at 13, just in the rear of the cam end and preferably upon the pivot pin of the anti-friction roller, the rear end of the lateral guard fitting in a vertical slot 14 of the lateral projection 15 of the top guard, the projections and slots being provided in duplicate at the sides of the top guard to accommodate the two lateral guards. The lateral guards have sliding adjustment in the slots 14 when they are raised upon their pivots, and are limited in their downward movement by stop projections 16, engaging the upper surface of the top guard. The lateral projections or lugs 15 of the top guard being extended downwardly below the upper plate part of this guard, and the slots 14 being likewise extended, the lateral guards will be held accurately to movement in a vertical plane.

Should it be required to tilt the saw table to a high angle as great as 45 degrees, the inner of the lateral hinged guards will be automatically adjusted to still guard the saw in proper manner, being raised upon its forward hinge by contact with the upper surface of the table. The outer of the lateral guards will, in the tilted position of the table, and in its normal position, still guard the saw at this side. Either of the lateral guards may be raised upon its pivot to inspect the saw or the wood.

As the wood leaves the saw, the saw kerf in the wood will engage the vertical blade standard 6 which is of proper thickness for this purpose, the sides of the kerf being in this way prevented from closing upon the saw, which would cause a sudden backward movement or kick of the wood very dangerous to the operator.

The blade standard 6, is sharpened to a knife edge in front, and is preferably removably fitted in a slot 17, of the yoke 6', the standard having a notch 18, in its bottom engaging a pin 19, of the yoke, the rear edge of the standard bearing against a pin 20, of the yoke.

What I claim is:

1. In a saw guard, a supporting member, and a normally substantially horizontal side guard at each side carried by said supporting member both side guards being loose and independently movable with relation to each other, whereby they are capable of assuming simultaneously different inclinations.

2. In a saw guard, a supporting member pivoted in rear, and a normally substantially

horizontal side guard at each side pivoted in front to said supporting member both side guards being loose and independently movable upon their pivots with relation to each other, whereby they are capable of assuming simultaneously different inclinations.

3. In a saw guard, a top guard pivoted in rear and having lateral guides, a normally substantially horizontal side guard at each 10 side pivoted in front to said top guard, both side guards working in rear in said rear

guides and being loose and independently movable upon their pivots with respect to each other, whereby they are capable of assuming simultaneously different inclinations. 15

In testimony whereof I affix my signature, in presence of two witnesses.

GEORGE H. ADAM.
